UNITED STATES PATENT OFFICE.

LOUIS ROTHMAN, OF BROOKLYN, NEW YORK.

ADDING MACHINE.

Application filed March 9, 1923. Serial No. 623,976.

To all whom it may concern:

Be it known that I, LOUIS ROTHMAN, a citizen of the United States, residing at Brooklyn, in the county of Kings and State 5 of New York, have invented certain new and useful Improvements in Adding Machines, of which the following is a specification.

This invention relates to adding machines, 10 being designed more particularly for embodiment in small machines which may be readily carried around in the pocket of the user, the invention having for an object to provide an improved and simplified adding machine of this type.

For further comprehension of the invention, and of the objects and advantages thereof, reference will be had to the following description and accompanying drawings, and to the appended claims in which the various novel features of the invention 20 are more particularly set forth.

Fig. 1 of the drawings is a face view of my improved adding machine.

Fig. 2 is a side view thereof.

Fig. 3 is a horizontal section on the line 3—3 of Fig. 1.

Fig. 4 is a transverse vertical sectional view on the line 4—4 of Fig. 1.

Fig. 5 is a horizontal sectional view taken on the line 5—5 of Fig. 4.

Fig. 6 is a fragmentary vertical section taken on the line 6—6 of Fig. 5.

Fig. 7 is an elevation of one of the number wheels.

As here embodied my improved adding machine comprises a flat rectangular casing 10 closed on all sides. Extending across this casing near one end thereof is a normally fixed shaft 11 which is mounted at its ends in the side walls of the casing. Upon this shaft are freely mounted a number of number carrying wheels 12 which are adapted for rotation in the adding process, further reference being made in detail to these wheels later. The peripheries of these wheels are arranged to present, in axially projected relation to one another, a pair of ratchet wheel elements 13 and 14 between which are short cylindrical parts, freely surrounded by ring-gears 15 carrying spring pressed pawls 16 engaging ratchet elements 14 whereby rotation is imparted from the gears 15 to the wheels as a whole.

These gears 15 are adapted to receive

rotary movement from rack-bars 18 slideable on the bottom wall of the casing. These rack-bars are operated by means of pinions 19 on a second shaft 20 parallel to the shaft 11 in the casing 10 and journaled in the side walls of the casing. On one end of this shaft is fixed a gear 22 which is adapted to be engaged by a rack-bar 23 slideable on the top wall of the casing and having a projecting handle 24 which extends through a longitudinal slot 25 in the top wall of the casing. The pinions 19 are loose upon the shaft 20 and have a yielding operative or slip clutch, engagement with the shaft 70 through the medium of spring fingers 27 fixed to collars 28 on the shaft and having obtuse angled transverse members 29 on their ends engaging in shallow V-notches 30 in the periphery of a disk element 31 formed integral with the gears 19.

The rack-bars 18 are adapted to be set for a determinate movement to be given the wheels 12 by means of keys in the form of pins 35 extending through the top wall 80 of the casing and suitably guided in apertures therein, these pins having heads 35' on their outer ends on which are printed the numbers. These pins are arranged in longitudinal rows, ten to a row and there are as many rows as it may be desired, each row representing a column of figures.

Upon the rear ends of the rack-bars 18 are offsets or lugs 18' which are adapted to engage the inner ends of the pins 35 when the latter are pushed inwardly, these pins being normally held clear of the paths of the lugs 18' by means of expansion springs 37 coiled therearound. Upon the inner ends of the pins are pivoted as at 38 hooked latches 39 having beveled ends, and which are adapted when the pins are pushed in, to pass through openings 40 in a plate 41 positioned in front of the rack bars 18 and into the path of movement of the lugs 18'. The pins 35 and latches 39 have abutment surfaces meeting along the lines 42 whereby turning or swinging of the latches from alignment with the pins in one direction is prevented, the pins carrying springs 43 105 which bear on the latches and return them to normal position when swung in the other direction.

To release the latches 39 the plate 41 is made slideable in suitable guides and has a pin 42' fixed to its rear end and projecting through the end wall of the casing, de-

pression of this pin causing the plate to move and free the latches from engagement therewith. In describing the relation of the parts the top wall or face of the casing 5 is the one through which the keys extend, while as regards the various members that move longitudinally of the casing I refer to the ends thereof which are normally nearest the wheels 12 as their forward ends. 10 The plate 41 is held in normal position by means of an expansion spring 44 coiled around the pin 42' and of sufficient strength to resist the pressure of the beveled ends of the latches as the latter move inward 15 through the openings 40 in the plate.

The rack-bars 18 are normally out of engagement with the pinions 19 and ring-gears 15 and means are provided so that when any pin of a given row is depressed 20 the corresponding rack-bar will be moved forward to engaging position with respect to its pinion and ring-gear. As shown in the drawing the ring-gear and pinion which are engaged by a common rack-bar are 25 slightly off-set from one another in the direction of their axes and the rack-bar is of sufficient width to engage both, while it has at its forward end a narrower portion 18' which engages only the ring-gear, passing 30 freely by the pinion, so that when the rack-bar is moved forward it simultaneously engages the pinion and ring-gear.

To effect this forward movement of the rack-bar when any one of the corresponding 35 row of pins is pushed in I form on the key-pins 35 the cam projections 47 adapted to engage complementary projections 48 on a series of slides 49 slidable in the casing above the plate 41 and which have slots 50 therein 40 through which the pins pass freely. The rear ends of these slides abut against the upper ends of levers 51 fulcrumed between their ends as at 52 in the casing and whose lower ends bear against the rear end of the 45 rack-bars 18. The slides 49 are held in normal position by means of coiled expansion springs 53 which bear against the rear ends thereof.

Referring now in detail to the wheels 12, 50 these are formed, in addition to the ratchet elements 13 and 14, with printing type 56 to print the numbers from zero to nine while adjacent the type are smooth surfaces on which may be marked like numbers which 55 are visible one at a time through apertures 57 in the face of the casing. Mounted in the casing are the spring pressed centering pawls 58 which engage in suitable notches 59 in the peripheries of integral projections 60 60 on the wheels. Each wheel may, in addition be frictionally held against rotation on the shaft 11 by means of a spring element 61 fixed to the shaft and bearing against one end of said wheel. The transfer mechanism 65 from one wheel to the next consists of an

arm 62 pivoted on the wheel and adapted to be moved into engagement with the ratchet element 13 on the adjacent wheel by a cam 63 fixed to the bottom wall of the casing.

The type 56 are adapted to print on a 70 paper strip 65 which is mounted in the casing in the form of a roll on a mandrel 66 in the latter and which passes up between a pair of rollers 67 and out through an opening 68. The paper is adapted to be moved 75 against the type by means of a platen bar 70 fixed on one end of a series of slide-bars 71 slidable in the casing and whose other ends are engaged by cams 72 on a rock-shaft 73. This rock-shaft has fixed thereto an arm 80 74 (Fig. 2) to which is connected one end of a link 75 which extends rearwardly along the bottom wall of the casing and has an offset 75' on its rear end adapted to be engaged by a pin 23' (Fig. 3) on the rack-bar 23 to 85 rock the shaft 73.

Fixed to the rollers 67 are gears 78 whereby the rollers are caused to rotate to feed the paper, these gears being operated by a train 79, the initial one of which receives 90 movement from rack-teeth 80 formed on one of the slide-bars 71. The platen bar 70 is moved away from the type by means of expansion springs 81 coiled around the slide-bars 71. In connection with one of the gears 95 79 is a ratchet and pawl device 79' to provide for one-way movement only.

The sheet containing the figures which are being added may be passed around a roll 85 carried in a housing 86 projecting from the 100 face of the casing, being held in contact with such roll by hinged fingers 87 while a pointer 88 may be provided to indicate the row of numbers, this pointer being adjustable along a bar 89.

In the operation of my improved adding machine, assuming that numbers of several integers are being added, the corresponding 105 keys 35 in the proper rows are first depressed by a stylus suitably attached on the index 110 finger. Upon depression of these keys the slides 49 will be shifted and will cause the proper rack-bars 18 to move forward to engage the pinions 19 and gears 15. The handle 24 is then pulled, rotating shaft 20 and 115 causing the engaged rack-bars to move forward and advance the corresponding ones of the wheels 12. As each rack-bar moves forward its lug 18' abuts against the latch of the depressed key and further movement 120 of the rack-bar is prevented, the spring fingers 27 riding over the element 31 as rotation of the shaft 20 is continued, the movement of the rack-bars being limited at the desired point by suitable stop elements. 125 When the handle 24 is moved forward again by spring 24' the gears 15 rotate back freely on the wheels 12. The front ends of the rack-bars 18 may project through openings 130 10' in the casing when moved forward.

Having thus described my invention, what I claim as new and desire to protect by Letters Patent of the United States is as follows:

- 5 1. In an adding machine, a casing, a row of keys, a number-carrying wheel, and an operating device for said wheel, said operating device comprising a movable member associated with the row of keys and adapted
- 10 to have its movement limited by selective individual engagement with the inner ends of the keys when the said keys are depressed, said movable member being normally out of engagement with the said wheel, and means
- 15 whereby said movable member is moved into engagement with the said wheel by depression of any one of said keys.
2. In an adding machine, a casing, a row of keys, a number-carrying wheel, and an op-

erating device for said wheel, said operating device comprising a movable member associated with the row of keys and adapted to have its movement limited by selective individual engagement with the inner ends of the keys when the said keys are depressed, 25 said movable member being normally out of engagement with the said wheel, and means whereby said movable member is moved into engagement with the said wheel by depression of any one of said keys, said means comprising a plate slidable in the casing, and hooked latches pivoted on the inner ends of the said keys and adapted to be engaged by said plate.

In testimony whereof I have affixed my 35 signature.

LOUIS ROTHMAN.
